UNITED STATES PATENT OFFICE.

KNUT O. B. TEXTORIUS, OF NEW YORK, N. Y., ASSIGNOR TO TEX ENGINEERING CORPORATION, OF NEW YORK, N. Y.

TIRE-FORMING CORE.

1,408,044.

Specification of Letters Patent. Patented Feb. 28, 1922.

Application filed May 27, 1921. Serial No. 473,088.

To all whom it may concern:

Be it known that I, KNUT O. B. TEXTORIUS, a citizen of the United States, and a resident of the borough of Manhattan, city, county, and State of New York, have invented certain new and useful Improvements in Tire-Forming Cores, of which the following is a specification.

This invention relates to an improved tire forming core and in its broadest aspect comprehends a collapsible core of this character including a plurality of relatively movable sections which are so constructed and connected to each other that a maximum of 15 strength and durability is obtained.

It is the primary object of the present invention to provide a collapsible core having a plurality of relatively movable sections connected to each other by concealed hinges. 20 These hinges are so constructed and arranged that they are wholly disposed within the area of the core body thus eliminating parts projecting from the peripheral face of the core which are liable to be broken off or so 25 bent or distorted as to render the core practically useless.

It is also an additional object of this invention to provide a key section adapted to be assembled with the hingedly connected 30 core sections so that said sections together form a continuous annular core, and means coacting with the opposed ends of the several core sections for effectively resisting lateral pressures in the direction of the core 35 axis and preventing the relative displacement of said sections so that they are at all times retained in true circumferential alignment with each other.

Specifically, the present improvement 40 templates a collapsible core which is particularly designed for use in connection with machines for making cord tires, such for instance as is disclosed in my co-pending application Serial No. 473,087, filed of even 45 date herewith. To this end, in one embodiment of the invention, I provide each section of the core inwardly of the cylindrical body thereof concentric longitudinal flanges projecting from opposite sides of the core. 50 When the core sections are in their operative positions to provide a continuous annular core structure, these flanges are in circumferential alignment with each other and provide continuous annular seats upon which 55 the ends of the cord layer arranged upon the

cylindrical body of the core are adapted to be disposed and to which the cord ends may be securely clamped.

With the above and other objects in view, the invention consists in the improved collapsible tire forming core and in the form, construction and relative arrangement of its several parts as will be hereinafter more fully described, illustrated in the accompanying drawings and subsequently incorporated in the subjoined claims.

In the drawings wherein I have illustrated one desirable and practical embodiment of the invention and in which similar reference characters designate corresponding parts throughout the several views.

Figure 1 is a plan view of the improved core showing the several parts thereof properly assembled into annular form, certain portions being in section to more clearly illustrated the construction;

Figure 2 is a transverse section taken on the line 2—2 of Figure 1;

Figure 3 is a section taken on the line 3—3 of Figure 1;

Figure 4 is a fragmentary longitudinal section taken on the line 4—4 of Figure 1;

Figure 5 is an enlarged detail fragmentary section illustrating the locking ring and the manner in which it coacts with the core sections;

Figure 6 is a plan view showing the hingedly connected sections of the core collapsed or folded;

Figure 7 is a plan view of the key section of the core, and

Figure 8 is an inverted plan view of the locking ring.

Referring in detail to the drawings, 5, 6 and 7 respectively, indicate three core sections, the section 5 being comparatively long while the section 6 is of somewhat less circumferential length and the section 7 appreciably shorter than the section 5. However, the length of these core sections is 100 more or less arbitrary and a greater or less number of the core sections might be used if desired. The core sections 5, 6 and 7 are of identically the same cross-sectional form, each section having a hollow spherical body portion 8, the inner side of which is provided with a centrally located circumferentially continuous laterally projecting web 9 extending in a radial plane coincident with the axis of the core body 8. As herein 110

shown, this web has a longitudinally continuous flange 10 on each side thereof, said flanges being disposed in concentric relation to the core body 8 and projecting from the web 9 in substantially parallel relation to the radial axis of the core.

Inwardly of the flanges 10, the web 9 has a longitudinal groove or channel 11 formed in one face thereof, such channel being concentric to the adjacent flange 10. The outer side wall 12 of the groove or channel 11 is obliquely inclined outwardly from the base wall of said channel and the inner side wall 13 of the channel is likewise inclined outwardly from the base wall thereof. At the opposite side of the web 9, a second flange 14 is formed thereon and is spaced inwardly from the flange 10 and in concentric relation therewith. With the latter flange 14 suitable lifting means is adapted to be engaged whereby the core may be conveniently transported from place to place.

At the inner side of the core section 5 and at each end thereof the inner portions of the core section including the web 9, the flanges 10 and flange 14, are extended beyond the end face of the core body 8 as indicated at 15 and these extensions are recessed or mortised as indicated at 16. The mortises 16 receive longitudinally projecting ears 17 on one end of each of the core sections 6 and 7 respectively. These ears and the spaced parts of the extensions 15 are provided with openings which receive the hinge pintles 18. The ends of these hinge pintles are countersunk, one end thereof in the base wall of the groove or channel 11 and the other end in the face of one of the parts 15. It will be observed from a comparison of Figures 2 and 3 of the drawings that the flanges 14 do not extend upon the hingedly connected projections 15 and 17 of the core sections. It will also be noted that these hinged lugs or projections 15 and 17 are located wholly within the transverse area of the core structure and no parts thereof project from the inner periphery of the core when the several sections are arranged in circumferential alignment as seen in Figure 1. In other words, the hinge connections between the several core sections may properly be referred to as being concealed. Therefore, these parts are protected against liability of accidental breakage or distortion when the core is roughly handled.

The opposite ends of the hollow body 8 of each core section are closed by the walls 19. In the walls 19 of the core section 5 the elliptical shaped interlocking lugs 20 are fixed by means of the pins 21 extending transversely through the wall 19 and through an opening in the lug. These lugs are disposed in a plane parallel with the core section and coincident with the axis of the body portion 8. One-half of each of the

elliptical lugs project beyond the end face of the core section and are adapted for engagement with a correspondingly shaped recess or pocket 22 formed in the opposed ends of the core sections 6 and 7 respectively 70 when the sections are arranged as seen in Figure 1.

The key section 23 of the core is of the same cross-sectional form as the hingedly connected sections 5, 6, and 7, the body portion thereof being likewise closed at its opposite ends by the walls 24. The end faces 25 of this key section extend in converging relation towards each other from the inner to the outer side of said core section as 80 clearly shown in Figure 7 and the opposed end faces 26 of the core sections 6 and 7 are correspondingly inclined and converge towards each other when the several hingedly connected sections are disposed in 85 circumferential alignment.

The end walls 24 of the key section are provided with the transversely extending recesses 27 which gradually increase in depth from their inner to their outer ends, the latter ends of said recesses opening upon the outer peripheral face of the core section. In the walls 19 of the free ends of the core sections 6 and 7 the wedge shaped keys 28 are fixed upon the pins 29. These keys 28 and the key lugs 20 retain the several sections of the core in true circumferential alignment and prevent their relative displacement by pressure exerted against opposite sides of the core sections. These key 100 lugs thus prevent the possible distortion of the hingedly connected projections 15 and 17 of the core sections.

In assembling the several sections of the core, after the two sections 6 and 7 have 105 been swung outwardly into circumferential alignment with the intermediate section 5, the key section 23 is disposed between the sections 6 and 7 and moved outwardly in a radial direction between the end faces 26 of 110 said core sections. The end faces 25 of the key section exert a gradually increasing frictional wedging action against the end faces 26 as the key lugs 28 carried by the sections 6 and 7 move into the recesses 27 of the key 115 section. This wedging action continues until the inner and outer peripheral surfaces of the key section 23 are brought into circumferential alignment with the corresponding surfaces of the sections 6 and 7 and during this movement said latter sections are expanded outwardly into proper circumferential alignment with the intermediate section 5 and with the opposed end faces of the sections 5, 6 and 7 in tight abutting contact with each other. Thus there is produced a continuous annular core structure 125 wherein the flanges 9 and 10 and the channels 13, as well as the body portions 8 of the several core sections are in perfect cir-

130

cumferential alignment with each other and of unbroken continuity.

The several sections of the core may now be easily, quickly and securely locked together against all possibility of accidental collapse by means of the locking ring 30. This ring, as shown in Figure 5 of the drawings, has a body portion provided with a transversely inclined outer face 31. The 10 inner face 32 of this ring is also transversely inclined, but the inclination of said inner face is appreciably greater than that of the outer face 31 of the ring with respect to ring axis and said inner face 32 is inclined 15 in the opposite direction with respect to said outer face. In other words, the inner and outer faces of said ring are convergently inclined on different lines with respect to the central median plane of the ring which 20 is parallel to the ring axis. Accordingly it will be seen that the said ring tapers in thickness and may, therefore, be easily and quickly inserted into the aligned grooves or channels of the several core sections. When 25 the ring is thus applied, the outer face 31 thereof has sliding frictional contact with the wall 12 of the channel 11, the degree of inclination of said face of the ring and the channel wall being substantially the same. 30 The inner face 32 of the ring however, has a much greater degree of inclination than the inner wall 13 of the channel so that the ring face 32 has frictional contact only upon the corner formed at the meeting edge 35 between the channel wall 13 and the face of the web 9. As the ring is forced into the channel 11, it will tend to rock upon this corner as a fulcrum and the opposite or outer face of the ring will thereby be urged 40 into tight frictional contact against the channel wall 12. Owing to this single annular line of contact of limited area between the inner face of the ring 30 and the inner wall of the channel 11, wear of the ring is more 45 effectively taken up or compensated for and a tight connection assured at all times.

The body of the ring 30 is further provided with an annular groove or channel 33 which opens upon the relatively narrow 50 edge face of said ring which is opposed to the base wall of the channel 11 when the locking ring is inserted. This channel provides for elasticity in the ring structure and obviates the tendency of displaced air to 55 resist the entrance of the ring into the channel, which air under expansion, tends to force the ring outwardly from the channel. At the other or wider edge of the ring, an inwardly extending annular flange 34 is 60 formed thereon which provides convenient means whereby the locking ring may be readily displaced and removed from the channels 11 when it is desired to collapse the sections of the core.

65 It will be apparent that when the several

core sections have been properly assembled and locked together by means of the ring 30, said core may be properly handled and moved from place to place without danger of displacement of the key section 23 and 70 the collapse of the core structure. Such collapse may, however, be easily effected by simply removing the locking ring 30 and then forcing the key section 23 radially inward and removing said section. The sections 5, 6 and 7 can then be relatively folded into compact relation as seen in Figure 6 of the drawings. These hingedly connected core sections constructed in the manner above explained will withstand very hard usage 80 and together with the key section, can be easily and quickly assembled into the complete annular core structure.

From the foregoing description taken in connection with the accompanying drawings, 85 the construction, manner of use and several advantages of my improved tire forming core will be fully understood.

While I have herein referred to a core of peculiar cross sectional form especially designed for use in connection with machines for building cord tires it will be readily understood that the core may also be produced in various other cross sectional shapes. Thus I have herein shown the core as provided with the flanges 10 upon which the ends of the cord layer applied upon the body 8 are adapted to be clamped and also with the concentric grooves 10' at the outer side of each flange 10 and at the base thereof of which are adapted to receive suitable beads applied to the marginal portions of the cord layers. It will be apparent, however, that insofar as the means for connecting and assembling the several sections 90 of the core is concerned, these features might be eliminated. Also the invention, as above described is susceptible of many modifications in the form, construction and arrangement of its several parts and the essential 95 features thereof may be incorporated in numerous alternative structures. Accordingly, I reserve the privilege of adopting all such legitimate modifications as may be fairly embodied within the spirit and scope 100 of the invention as claimed.

I claim:

1. A tire forming core comprising a plurality of arcuate sections, hinges inseparably connecting said sections to each other, a 120 key section coacting with certain of the first named sections to position the core sections in circumferential alignment with each other, and a single locking means common to all of said core sections for holding the 125 same against relative displacement.

2. A tire forming core comprising a plurality of arcuate sections, concealed hinges inseparably connecting said sections to each other and disposed wholly within the area 130

- of the core structure, a key section coacting with certain of the first named sections to position the core sections in circumferential alignment with each other, means coacting 5 with the abutting ends of the several core sections to resist pressures against opposite sides of the core in the line of its axis, and locking means common to all of the core sections for holding said sections against 10 relative radial displacement.
3. A tire forming core comprising a plurality of arcuate core sections, hinges inseparably connecting said core sections to each other at their inner sides and wholly 15 concealed within the core structure whereby the inner faces of the core sections are substantially unbroken by projecting parts of the hinges when said sections are disposed in circumferential alignment, lugs fixed in 20 the ends of one of said core sections, the opposed ends of the other core sections having recesses to receive said lugs, additional lugs fixed in the ends of the latter core sections and projecting from the end faces 25 thereof, a key section adapted to be positioned between said ends of the latter core sections and frictionally coacting with the end faces thereof to position the several sections in circumferential alignment with 30 each other, said key section having recesses in its opposite end faces to receive the last named lugs, and means common to all of said core sections to lock the same against relative radial displacement.
- 35 4. A collapsible tire forming core comprising a plurality of hingedly connected inseparable core sections and a key section adapted, when assembled, to form a continuous annular core structure, each of said 40 core sections having a longitudinal groove in one side thereof, and an annular locking ring having means to frictionally coact with the walls of said grooves when the core sections are assembled to lock the several sections 45 of the core against relative radial displacement.
5. A collapsible tire forming core comprising a plurality of hingedly connected inseparable core sections and a key section 50 adapted, when assembled, to form a continuous annular core structure, each of said core sections having a longitudinal groove in one side thereof, said grooves being disposed in alignment with the connecting 55 hinges between the core sections transversely of said sections, and an annular locking ring having means to frictionally coact with the walls of said grooves when the core sections are assembled to lock the several sections 60 of the core against relative radial displacement.
6. A collapsible tire forming core comprising a plurality of hingedly connected inseparable core sections and a key section,

said sections when assembled, forming a continuous annular core structure, each of the core sections having a longitudinal groove in one of its side faces, the opposite side walls of said grooves being beveled, an annular locking ring having its opposite side faces beveled in relatively opposite directions and the inner face thereof having a greater degree of inclination than the outer face to frictionally coact with the inner walls of the grooves in the core sections when the locking ring is inserted in said grooves and thereby exert an expanding force against the ring to urge the outer face thereof into tight frictional engagement with the outer walls of said grooves whereby the several 80 core sections are held against relative radial displacement.

7. A collapsible tire forming core, comprising a plurality of core sections adapted to be assembled to form a continuous annular core, each of the core sections having a longitudinal groove in one of its side faces, the opposite side walls of said grooves being beveled, an annular locking ring having its opposite side faces beveled in relatively opposite directions and the inner face thereof having a greater degree of inclination than the outer face to frictionally coact with the inner walls of the grooves in the core sections when the locking ring is inserted in 95 said grooves and thereby exert an expanding force against the ring to urge the outer face thereof into tight frictional engagement with the outer walls of said grooves, whereby the several core sections are held against 100 relative radial displacement.

8. A tire forming core comprising a plurality of arcuate sections, hinges inseparably connecting said sections to each other, a key section coacting with certain of the first named sections to position the core sections in circumferential alignment with each other, and means for holding the assembled core sections against relative displacement.

9. A tire forming core comprising a cylindrical body, having a central web on its inner side extending radially therefrom and substantially circumferentially continuous with the core body, cord end seating flanges projecting from said web at opposite sides 115 thereof intermediate of said body and the inner edge of the web and having their edge faces upon which the marginal edges of the cord layers are adapted to be engaged, disposed beyond the opposite side faces of the 120 inner portion of the web in spaced relation thereto out of coinciding relation with the planes of the opposite side faces of the inner portion of said web.

In testimony that I claim the foregoing as 125 my invention, I have signed my name hereunder.

KNUT O. B. TEXTORIUS.
